James T. Forsythe

United States Patent Office.

JAMES T. FORSYTH, OF WHEELING, WEST VIRGINIA.

Letters Patent No. 82,613, dated September 29, 1868.

IMPROVEMENT IN MACHINES FOR DRESSING BARREL-HOOPS.

The Schedule referred to in these Letters Patent and making part of the same.

TO ALL WHOM IT MAY CONCERN:

Be it known that I, JAMES T. FORSYTH, of the city of Wheeling, county of Ohio, in the State of West Virginia, have invented a new and useful Machine for Dressing Barrel and other Hoops from split timber; and I do hereby declare that the following is a full, clear, and exact description of the construction and operation of the same, reference being had to the annexed drawings, making a part of this specification, in which—

Figure 1 is a front elevation, and

Figure 2 is a transverse section.

Like letters represent like parts.

The nature of my invention consists in the combination and arrangement of the different parts of a circular revolving bed-piece, working inside of a stationary concentric ark in such a manner that it will automatically catch the end of the piece of stuff to be dressed, whilst the machine is in motion, and draw it under the dressing-knives, so as to give it the desired thickness and shape for a barrel or other hoop, and, when finished, discharge the same, thereby obviating the difficulty of the slipping of the piece whilst being fed to the machine.

The object of my invention being the formation and dressing of barrel and other hoops from split timber, in the drawings, fig. 1 represents a front elevation of my machine, and fig. 2 a transverse section.

Letter A represents the stationary concentric ark, which is secured to the frame C C C by the bolts Q.

Letter B represents the revolving bed-piece, which is attached to the shaft O, it being hung on the frame C C C in such a manner that the bed B will revolve inside of the concentric ark A, motion being given by the driving-wheels marked P.

Letter D represents a hinged catch, so attached to the bed B that as the bed revolves, the catch D, coming in contact with the enlargement, represented by the red line on the circular ark at R, it is forced down and catches the piece of wood between it and the spring F, and thereby drawing it under the press-rolls, marked G, and the knife H; and as it passes round to the end of the enlargement, represented by the red line at S, the catch being released, it is thrown up preparatory to taking hold of the next piece, and the finished hoop is discharged at the other end of the machine.

The letter m represents an enlargement or raise on the bed B, for the purpose of giving the proper shape to the hoop.

Letter K represents a bit or knife, which is attached to the bit-stock, represented by the dotted line I, and extends down past the bed B in such a manner that it will separate any surplus wood from and at the same time dress the edge of the hoop.

The press-rolls G are held down by the springs L, the machine to be operated by any of the usual or well-known powers.

Having thus described my invention, what I claim, and desire to secure by Letters Patent of the United States, is—

1. The circular revolving bed B, the catch D, and the spring F, or their equivalents, substantially as described.

2. The concentric ark A, in combination with the knives H H and K K, substantially as described, and for the purpose set forth.

JAMES T. FORSYTH.
